UNITED STATES PATENT OFFICE

EARL E. EICKMEYER, OF DAYTON, OHIO, ASSIGNOR TO THE DAYTON PUMP & MANUFACTURING COMPANY, OF DAYTON, OHIO, A CORPORATION OF OHIO

DESIGN FOR A LIQUID-DISPENSING PUMP

Application filed June 23, 1930. Serial No. 36,131. Term of patent 3½ years.

To all whom it may concern:

Be it known that I, EARL E. EICKMEYER, a citizen of the United States, residing at Dayton, in the county of Montgomery and State of Ohio, have invented a new and ornamental Design for a Liquid-Dispensing Pump, of which the following is a specification, reference being had to the accompanying drawings, forming a part thereof.

In the accompanying drawings:

Figure 1 is a front elevation of the liquid dispensing pump showing my new design;

Figure 2 is a top plan view thereof;
Figure 3 is a section on the line 3—3 of Figure 1; and

Figure 4 is a side elevation of the upper part of the pump of my design.

I claim:

The ornamental design for a liquid dispensing pump as shown.

EARL E. EICKMEYER.
